(57) **CLAIM**

The ornamental design for a dust filter for cleaning appliance as shown and described.

DESCRIPTION

1. Dust filter for cleaning appliance

1.1 : Front

1.2 : Back

1.3 : Left

1.4 : Right

1.5 : Top

1.6 : Bottom

1.7 : Perspective

1.8 : Perspective

Reproduction 1.1 is a front view of a dust filter for cleaning appliance; reproduction 1.2 is a back view thereof; reproduction 1.3 is a left view thereof; reproduction 1.4 is a right view thereof; reproduction 1.5 is a top view thereof; repro-

(Continued)

duction 1.6 is a bottom view thereof; reproduction 1.7 is a front perspective view thereof; and reproduction 1.8 is a rear perspective view thereof.
